CLAIM

The ornamental design for a file sheet for magnetic recording media, as shown and described.

DESCRIPTION

FIG. 1 is a front elevational view of a file sheet for magnetic recording media showing my new design;

FIG. 2 is a rear elevational view thereof;

FIG. 3 is a bottom plan view thereof;

FIG. 4 is a left side elevational view thereof;

FIG. 5 is a right side elevational view thereof;

FIG. 6 is a sectional view taken on line 6—6 of FIG. 1; and

FIG. 7 is a sectional view taken on line 7—7 of FIG. 1.

FIG. 1

FIG. 2

FIG. 3

FIG. 4

FIG. 5

FIG. 6

FIG. 7
